UNITED STATES PATENT OFFICE.

SPENCER G. NEAL, OF LOS ANGELES, CALIFORNIA, ASSIGNOR TO CALIFORNIA VALVE
AND AIR BRAKE COMPANY, OF LOS ANGELES, CALIFORNIA, A CORPORATION OF
CALIFORNIA.

AUXILIARY-PRESSURE-CONTROL VALVE.

1,091,754.

Specification of Letters Patent. Patented Mar. 31, 1914.

Application filed July 29, 1913. Serial No. 781,834.

To all whom it may concern:

Be it known that I, SPENCER G. NEAL, a citizen of the United States, residing in the city of Los Angeles, State of California, have invented a new and useful Auxiliary-Pressure-Control Valve, (Case B,) of which the following is a specification.

In the operation of railway braking systems now in general use, no provision is made to safeguard against over-charging the auxiliary reservoirs when the auxiliary pressure is renewed after there has been an application of the brakes. That is to say, although the auxiliary reservoir pressure is not apt to be over-charged in the original charging of the train pipe and auxiliary reservoirs, nevertheless, after there has been an application of the brakes and it is desired to again charge the train pipe through the engineer's brake valve, this second or subsequent charging of the train pipe not infrequently results in over-charging the same, thereby bringing the pressure of the train pipe up so far above the pressure which the feed valve on the engine is set to maintain in the train pipe and auxiliary reservoir that leakage from the train pipe down to said set pressure, while the auxiliary reservoir still remains above said set pressure, will cause the triple valves to make an undesired service application of the brakes.

It is to be understood that this newly invented pressure control valve is to be assembled in combination with a triple valve constructed according to the principle of the triple valve described and claimed in my Patent No. 1,078,303, issued November 11, 1913. In order to adapt the triple valve of said patent to coöperate with the pressure control valve hereinafter described, it is not necessary to modify the construction of said triple valve but only to dispense with the over-charging valve of the same as will herein-after more fully appear.

Referring to the accompanying drawings which illustrate the invention: Figure 1 is a vertical mid-section of this pressure control valve, the line of section extending lengthwise through the brake cylinder passage. Fig. 2 is a diagram of the braking elements of a single car showing the relation

of the present invention thereto. Fig. 3 is a vertical mid-section on line x^3-x^3 of Fig. 1. Fig. 4 is a perspective view of one of the valve operating elements. Fig. 5 is a view repeating with slight change the fifth view of my above mentioned patent. This view shows the part of said triple valve which is modified in order to adapt the same to coöperate with the present invention.

Referring to Fig. 2 of the drawings, this auxiliary pressure control valve is designated in the diagram by the numeral 1, being connected with the auxiliary reservoir 65 by means of the feed pipe 3, and being connected with the brake cylinder 4, by the pipe 5. 6 designates the triple valve, 7 the train pipe and 8 a branch pipe connecting the control valve 1 with train pipe 7. 70

Within a casing consisting of the upper cap 11 and lower cap 12 is a movable abutment 13, preferably constructed as a diaphragm device having a lower supporting plate or follower 14, with an upward tubular extension 15, upon which is screwed the following plate 16, the diaphragm proper 17 being clamped between said plates 14 and 16. As shown in Fig. 1 the tubular extension 15 projects up considerably above the top of the diaphragm device or abutment 13 and is surrounded by an extension 18 with which the cap 1 is provided. A bushing or bearing sleeve 19 is interposed between the cap extension 18 and said tubular extension 15. 85

In order to operate certain valves which will hereinafter be described, there is provided a valve operating device designated in a general way by the numeral 21. Said valve operating device is shown in detail in Fig. 4, comprising a rectangular yoke or link 22, having a recess or slot 24 cut into the side of the lower end thereof and an upwardly extending operating stem 25 projecting from the upper end thereof. Said stem 25 extends up through the extension 15 of the diaphragm device already described and projects slightly thereabove. A stop nut 26 is screwed onto the upper end of stem 25, said stop nut being secured in place by lock nut 27. Around the bearing sleeve 19 is provided an annular space with

in which is seated a compression spring 28, which bears against the lower side of stop nut 26. At their upper end the parts just described are protected by a housing or air tight cap 29. The diaphragm extension 15 is provided with ports 31 which open into the auxiliary reservoir chamber 32 above diaphragm 17.

At the lower end of stem 25 is a valve 33 which, when open, allows air to pass from the chamber 34 through a slight clearance around the stem 25 and out said ports 31 into the auxiliary reservoir chamber 32 and thence by way of the auxiliary passage 35 and auxiliary feed pipe 3 to the auxiliary reservoir 2 as shown in Figs. 2 and 3.

Into the chamber 34 there projects from the side of the casing a combination conduit and valve supporting arm 41, the brake cylinder passage 42 thereof leading to a valve chamber 43 having an open lower end upon which is seated a release valve 44. The release valve 44 has at its upper end a winged portion 45 within the valve chamber 43 and at its lower end is provided with a neck 46 terminating in a head 47. Slot 24 of yoke 22 already referred to, engages said neck 46 to operate the valve 44 as will be later described.

At the lower end of the casing is a tubular extension 48 within which is screwed a tubular member 49 secured in place by a lock nut 51. Upon the upper end of tubular member 49 seats a train pipe valve 52 having a winged portion 53 moving within said tubular member 49. Beneath the winged portion 53 of valve 52 is preferably placed a compression spring 50 to assist in opening valve 52.

The parts just described are surrounded by a housing or screw cap 54 having at its lower end a port 55 in communication with the pipe 8 which leads to the train pipe 7, as shown in Fig. 2.

The case caps 11 and 12 have flanged portions which are preferably secured together by cap screws 56, the diaphragm proper 17 being clamped between said caps 11 and 12.

Reference is now made to Fig. 5, which is a reproduction of the fifth figure of my patent for triple valve hereinbefore referred to, except that the charging valve is rendered inoperative. Referring to Fig. 5, in order to adapt the braking system shown in Fig. 2, which embodies the triple charging device shown in Fig. 5, to coöperate with the pressure control valve which forms the subject of this invention, the charging valve 61 will be rendered inoperative by screwing down the nut 62 upon the extension 63 of head 64 so as to bring the charging valve proper 61 up against its seat, thus preventing said valve from unseating.

Operation: Referring to Fig. 1 which

shows the valve 52 open, in order to charge 65 the auxiliary reservoir the train pipe pressure will be raised and will enter through the branch pipe 8 beneath valve 52 passing by said valve and raising the pressure in the train pipe chamber 34 against the lower 70 side of the diaphragm device 13 until said diaphragm device is lifted from the charging valve 33 whereupon the air will escape past said valve through the clearance around stem 25 and out the radial ports 31 into 75 the auxiliary reservoir chamber 32, whence it will reach the auxiliary reservoir 2 through passage 35 and pipe 3. Air will thus continue to flow into the auxiliary reservoir until the pressure therein and in 80 the auxiliary reservoir chamber 32 has reached an equality with the pressure in the train pipe chamber 34, completing the charging operation. In making a train pipe reduction the air pressure in chamber 85 34 is reduced below that in the auxiliary chamber 32. Valve 52 being normally held away from its seat by spring 50 will allow reduction of train pipe pressure to likewise reduce the pressure in train pipe chamber 90 34, with the result that the excess pressure remaining in chamber 32 above the diaphragm device 13 will cause the diaphragm device to descend, first closing charging valve 33, and then opening valve 44. Continued 95 downward movement to the diaphragm device will cause the head 47 of valve 44 to force the lower valve 52 firmly to its seat. During this operation the opening of valve 44 releases the pressure in train 100 pipe chamber 34 into the brake cylinder. The result is that the pressure in the chamber 34 is put into direct communication with the brake cylinder and the brake cylinder pressure which results from this operation is registered within the chamber 34. Owing to the fact that the brake cylinder pressure during service applications at no time exceeds the pressure in the auxiliary reservoir, there will at no time be sufficient 105 pressure under the diaphragm device 13 to disturb the firm seating of the lower valve 52. The step of the operation which will next be described brings out the main feature of the invention which is to guard against 110 over-charging of the auxiliary reservoir after a service application of the brakes. To effect a release of the brakes the train pipe pressure is raised in the usual manner to or above an equality with the pressure in the auxiliary reservoir. A complete release of the brake cylinder pressure and a corresponding release of pressure within the main chamber 34 will then take place. The result will be that owing to there being no 115 pressure beneath the diaphragm device 13 but undisturbed auxiliary reservoir pressure above said diaphragm device, the valve 52

will not be disturbed by the train pipe pressure therebeneath, but will keep the train pipe pressure out of the chamber 34. It will not be possible to again charge the 5 auxiliary reservoir until after what I term a "service emergency" or else a "quick emergency" application of the brakes has taken place. By this I mean such an operation of the triple valve as will cause an 10 equality of pressure between the brake cylinder and auxiliary reservoir, thus causing an equality of pressure above and below the diaphragm device 13. This condition will permit spring 28 to raise the valve stem 25 15 together with the yoke 22 thus raising and closing valve 44, thus withdrawing the valve head 47 from engagement with valve 52. Valve 52 will, however, remain seated as long as the train pipe pressure is below that 20 in the brake cylinder. This condition will prevent brake cylinder pressure escaping back into the train pipe. If now the train pipe pressure be raised above the brake cylinder pressure the valve 52 will be raised 25 and train pipe pressure admitted to chamber 34. Train pipe pressure is admitted to chamber 34 above the auxiliary reservoir pressure in chamber 32 which will result in repeating the charging of the auxiliary reservoir as stated at the beginning of the description of the operation.

I claim:

1. In combination with the train pipe, brake cylinder, auxiliary reservoir and triple valve; a pressure control device comprising a casing, a movable abutment dividing said casing into two chambers, one of said chambers being in communication with the auxiliary reservoir, the other of said chambers 35 being an operating chamber, there being a passage extending through said abutment to afford communication between said auxiliary reservoir chamber and said operating chamber, a valve to control said passage, 40 said valve being operated by the movements of said abutment, a valve to control communication between said operating chamber and the brake cylinder, and another valve to control communication between said operating 45 chamber and the train pipe, the movement of said abutment toward said operating chamber first closing said valve for controlling the auxiliary reservoir air and then upon further movement closing the 50 valve which admits air from train pipe to the operating chamber.

2. In combination with the train pipe, brake cylinder, auxiliary reservoir, and triple valve; a pressure control device comprising 55 a casing, a movable abutment dividing said casing into two chambers, one of said chambers being in communication with the auxiliary reservoir and the other of said chambers being adapted to communicate

with the train pipe and brake cylinder, an auxiliary reservoir valve to control communication between said operating chamber and said auxiliary reservoir chamber, another valve to control communication between said operating chamber 70 and the brake cylinder, valve operating means operatively connected with said abutment to control said valves, said valve operating means maintaining the auxiliary reservoir valve closed whenever the other valve 75 is open, and a valve to control admission of air from the train pipe to said operating chamber.

3. In the braking apparatus, a brake cylinder, a train pipe, an auxiliary reservoir, a triple valve, an auxiliary pressure control valve, means to place said control valve into communication with the auxiliary reservoir, brake cylinder and train pipe, said auxiliary pressure control valve comprising 85 a valve construction to cut off all communication between said train pipe and auxiliary reservoir as long as said auxiliary reservoir pressure is undisturbed, during all service 90 braking.

4. In braking apparatus a brake cylinder, a train pipe, an auxiliary reservoir, a triple valve, a valve to charge the auxiliary reservoir from the train pipe, and means to automatically close said charging valve after 95 a service application of the brakes, said means maintaining said charging valve closed during all brake releasing operations until the auxiliary reservoir pressure and train pipe pressure are equalized, after which 100 equalization said valve is permitted to open.

5. In braking apparatus; a brake cylinder; a train pipe; an auxiliary reservoir; a triple valve; and an auxiliary pressure control valve comprising a casing, a movable 105 abutment dividing said casing into an operating chamber and an auxiliary reservoir chamber, means within said control valve to open communication between said operating chamber and the train pipe, and means to 110 automatically admit air from the operating chamber to the auxiliary reservoir while such communication exists.

6. In a braking apparatus, a brake cylinder, a train pipe, an auxiliary reservoir, a triple valve, a valve to charge the auxiliary reservoir from the train pipe, and means to automatically close said charging valve to prevent train pipe pressure from entering the auxiliary reservoir after a service application has been made and during all 115 brake releasing operations until the auxiliary reservoir pressure and the train pipe pressure have equalized.

7. In a braking apparatus, a brake cylinder, a train pipe, an auxiliary reservoir, a triple valve, a valve to charge the auxiliary reservoir from the train pipe, and means 120

to automatically close said charging valve and maintain the same closed during all service applications and brake releasing operations until the auxiliary reservoir pressure and the train pipe pressure have equalized.

In testimony whereof I have hereunto signed my name in the presence of two sub-

scribing witnesses at Los Angeles, in the county of Los Angeles and State of California, this 24th day of July, 1913.

SPENCER G. NEAL.
